UNITED STATES PATENT OFFICE.

GEORGE P. ALLEN, OF LOS ANGELES, CALIFORNIA.

COMBUSTION-PROMOTING DEVICE FOR INTERNAL-COMBUSTION ENGINES.

Application filed February 9, 1922. Serial No. 535,199.

To all whom it may concern:

Be it known that I, GEORGE P. ALLEN, a citizen of the United States, residing at Los Angeles, in the county of Los Angeles and State of California, have invented new and useful Improvements in Combustion-Promoting Devices for Internal-Combustion Engines, of which the following is a specification.

10 My invention relates to internal combustion engines for motor vehicles, and a purpose of my invention is the provision of an attachment for internal combustion engines by means of which additional passageways 15 are provided for increasing the supply of combustible mixtures other than that provided by the usual intake manifold, such mixtures being of the same or different character than that supplied from the engine's carburetor whereby, the general efficiency of an engine to which the attachment 20 is applied is greatly increased.

My invention further provides novel and more effective means for igniting the combustible mixtures supplied to the engine both by the attachment and the engine's carburetor which also tends to increase the power and efficiency of an engine.

I will describe one form of engine and 30 one form of attachment embodying my invention and will then point out the novel features thereof in claims.

In the accompanying drawings,

Figure 1 is a view showing in side elevation one form of internal combustion engine and one form of attachment embodying my invention, with portions thereof broken away to reveal parts not otherwise disclosed.

40 Fig. 2 is a fragmentary top plan view partly in section of the engine and attachment shown in Fig. 1.

Fig. 3 is a view showing the engine and attachment in front end elevation with portions thereof partly in section.

Referring specifically to the drawings in which similar reference characters refer to similar parts, my invention is shown applied to an internal combustion engine of 50 standard construction and including a cylinder block B, a cylinder head H having the usual spark plug openings P, a carburetor K, and an intake manifold M. The passage of gas from the carburetor to the 55 intake manifold is controlled by throttle valve V provided with an operating arm A

connected to an operating rod R which is connected to the throttle lever in the usual manner, as will be understood.

The attachment forming the subject 60 matter of my invention comprises in the present instance a subsidiary manigold M' consisting of an upper section 15 and a lower section 16, the latter being inserted in the usual joint provided between the carburetor K and the intake manifold M so as to be in communication with the carburetor. The section 16 is provided with a throttle valve V' to the stem of which is connected a spring 17 for normally urging the valve 70 to closed position. Another spring 18 is connected to the stem of the valve V' and to the arm A, this spring serving to provide an operative connection between the valves V and V' so as to cause the latter to 75 be operated simultaneously with the former. For the purpose of admitting air to the manifold M', a valve V² is provided in the section 16 at a point beyond the throttle valve V', and this valve is normally urged 80 to closed position by means of a spring 19. The stem 20 of the valve V² is operatively connected to the usual spark rod 21 by means of a wire 22 which is trained around the rod in the manner clearly shown in Fig. 85 3 so that when the rod is rotated an actuation of the valve is effected.

The upper end of the manifold M' is provided with a T 23 which is detachably connected to branch pipes 24 and 24^a having 90 vertical pipe extensions 25 and 25^a respectively that are also detachably associated with the branch pipes. The pipe extensions 25 and 25^a are internally formed with valve seats 26 including sleeves 27 in which the stems 28 of valves V³ are slidably fitted. Springs 29 surround the valve stems 28 above the sleeves 27 for normally urging the valves to closed position to prevent the passage of gaseous vapors from the manifold 95 M' through the pipe extensions. As clearly shown in Fig. 1, the pipe extensions 25 and 25^a are threaded within the spark plug openings P so that the manifold M' may be said to be in communication with 100 the upper end of the cylinders of the internal combustion engines, that is, when the valves V³ are in open position. The pipe extensions are formed with offset portions 27 which, as clearly shown in Fig. 3, are 110 internally threaded to receive spark plugs G of standard form and in such manner

that the terminals of the plugs are disposed in the path of movement of the gaseous vapors as they pass through the pipe extensions thereby utilizing the vapors in effecting a scavenging of the terminals.

In operation, the pistons of the engine not only operate to create a suction within the usual manifold M but also in the subsidiary manifold M' so that the combustible mixture emanating from the carburetor K is conveyed to the branch pipes 24 and 24^a. The suction created within the pipe sections 25 and 25^a is sufficient to overcome the tension of the springs 29 and thereby open the valves V², whereby the admission of the combustible mixture to the upper ends of the cylinders is effected and simultaneously with the admission of the mixture to the sides of the cylinders through the manifold M. The supply of current of the spark plugs G occurs in the usual manner so that the ignition of the combustible mixture within the respective cylinders takes place in the proper sequence. During the ignition of the mixture, the valves V² are naturally closed thus disconnecting the manifold M' from the cylinders in the same manner as the usual intake valves of an internal combustion engine.

From the foregoing operation taken in conjunction with the accompanying drawings, it will be manifest that the attachment provides additional means for supplying a combustible mixture to the cylinders of an engine at points other than through the usual intake valves, thereby greatly increasing the power and efficiency of the engine. It is clear that the attachment may be associated with any standard form of internal combustion engine without in any way modifying the construction of the latter, and that when in applied position it provides an additional area for the passage of the combustible mixture from the carburetor to the cylinders of the engine which serves to materially increase the power of the engine particularly when the engine is working under a heavy load.

The valve V² serves to supply additional air to the manifold M' as the spark of the engine is advanced, and this additional air supply obviously increases the combustible properties of the combustible mixture traversing the manifold M' and which is of course ultimately admitted to the cylinders of the engine.

Although I have specifically shown and described the attachment as providing a sub-

sidiary means for conducting the combustible mixture to the cylinders of the engine from the usual carburetor, it is to be understood that the manifold M' can be connected to another source of combustible mixture supply to conduct such mixture to the cylinders of the engine, and that this mixture can be of the same or of a different character than the mixture emanating from the carburetor K.

What I claim is:

1. In combination, an internal combustion engine having spark plug openings in the cylinder head, a carburetor, an intake manifold, a subsidiary intake manifold connected between the carburetor and the intake manifold, valve means for connecting the subsidiary intake manifold to the spark plug openings, ignition means carried by the last means, a throttle valve for controlling the passage of fluid from the carburetor to the intake manifold, a second throttle valve in the subsidiary intake manifold, and means operatively connecting the two throttle valves for effecting simultaneous operation of the two.

2. In combination, an internal combustion engine having spark plug openings in the cylinder head, a carburetor, an intake manifold, a subsidiary intake manifold connected between the carburetor and the intake manifold, valve means for connecting the subsidiary intake manifold to the spark plug openings, ignition means carried by the last means, a throttle valve for controlling the passage of fluid from the carburetor to the intake manifold, a second throttle valve in the subsidiary intake manifold, means operatively connecting the two throttle valves for effecting simultaneous operation of the two, and an air valve associated with the subsidiary intake manifold for controlling the supply of air to the latter.

3. An attachment of the character described comprising a manifold, branch pipes connected to one end of the manifold, pipe extensions connected to the branch pipes, valves within the pipe extensions to allow the passage of fluid outwardly of the pipe extensions, gas ignition means carried by the pipe extensions, a throttle valve within the manifold, an air port formed in the intake manifold, and a valve for controlling said port.

In testimony whereof I have signed my name to this specification.

GEORGE P. ALLEN.
